The Nike Air Max 90 Releases in a Vintage Friendly Blue and Orange [online], [retrieved May 10, 2019] retrieved from internet <URL: <https://sneakernews.com/2019/04/29/nike-air-max-90-blue-orange-aj1285-104/>>; 7 color sheets, Dated Apr. 29, 2019.

Primary Examiner — T Chase Nelson(74) Attorney, Agent, or Firm — Banner & Witcoff, Ltd.(57) CLAIM

The ornamental design for a shoe, as shown and described.

DESCRIPTION

FIG. 1 is a rear bottom perspective view of a shoe showing my new design;

FIG. 2 is a bottom view thereof; and,

FIG. 3 is an opposite side rear bottom perspective view thereof.

The four broken line regions and the unshaded areas therein form no part of the claimed design. The broken lines depicting the remainder of the shoe show features that form no part of the claimed design.

1 Claim, 3 Drawing Sheets---
